UNITED STATES PATENT OFFICE.

THOMAS C. MERRIMAN, OF TUNSTALL, ENGLAND, ASSIGNOR TO WILLIAM S. PITCAIRN
CORPORATION, A CORPORATION OF NEW YORK.

DESIGN FOR A COVERED DISH OR SIMILAR ARTICLE.

Application filed June 30, 1928. Serial No. 27,335. Term of patent 7 years.

To all whom it may concern:

Be it known that I, THOMAS C. MERRIMAN, a subject of the King of Great Britain, and resident of Tunstall, county of Stafford, England, have invented a new, original, and ornamental Design for a Covered Dish or Similar Article, of which the following is a specification, reference being had to the accompanying drawing, forming part thereof.

In Fig. 1 of the drawing is shown in a top plan view, a covered dish embodying my new design. Fig. 2 is a side view of the same.

I claim:

The ornamental design for a covered dish or similar article as shown.

THOMAS C. MERRIMAN.
